UNITED STATES PATENT OFFICE.

JOSHUA KAMES, OF PHILADELPHIA, PENNSYLVANIA, ASSIGNOR, BY MESNE ASSIGNMENTS, TO THE NATIONAL ELECTRIC CONDUIT COMPANY, OF CAMDEN, NEW JERSEY.

METALLIC CONNECTOR FOR ELECTRIC RAILWAYS.

SPECIFICATION forming part of Letters Patent No. 393,012, dated November 20, 1888.

Application filed January 12, 1888. Serial No. 260,571. (No model.)

To all whom it may concern:

Be it known that I, JOSHUA KAMES, a citizen of the United States, residing at Philadelphia, in the county of Philadelphia and State 5 of Pennsylvania, have invented new and useful Improvements in Metallic Connectors for Electric Motors for Railway-Cars, of which the following is a specification.

My invention relates to electrical mechanism for propelling street-cars and other conveyances, and the purpose thereof is to provide simple means whereby contact may be preserved between the main conductor or cable and the arm or arms taking the current 15 therefrom to the motor.

It is also my purpose to provide means whereby the rocking movement of the car, as well as the rise and fall of the frame by variations in the weight carried, may be automatically compensated.

It is my purpose, finally, to provide a simple insulating-bearing for the contact-arms, which shall avoid the necessity of lubrication and give complete insulation.

The invention consists in the several novel 25 features of construction and new combinations of parts, hereinafter fully set forth, and then definitely pointed out in the claims.

In the accompanying drawings, Figure 1 is 30 a vertical section of one end of a car and platform, showing the application of my invention. Fig. 2 is a plan view of the same. Fig. 3 is a vertical transverse section in the plane 3 3, Fig. 1. Fig. 4 is a detail view, enlarged, of 35 one of the contact-arms, the view showing said part in elevation and in section.

In the said drawings the reference-numeral 1 denotes a car of any ordinary type, having mounted thereon an electric motor of any 40 known or preferred construction, said motor, inasmuch as it forms no part of my present invention, not being shown in the drawings.

Rising from the floor of the casing, in which the motor is arranged, are vertical rods or 45 bars 2, which support a plate or spider, 3, secured to their top. Below this spider, and separated from it by spiral springs 4, encircling the rods 2, is a second plate, 5, from which depend arms or brackets 6 of substan-

tially equal length. These arms are formed 50 in pairs, one pair being at or near one end of the plate and the other pair at or near the other end.

Between each pair of arms or brackets is pivotally mounted an arm, 7, having two diverging arms, 8 and 9, projecting from it at or near the pivotal point. One of these arms, 8, is a contact, and is adapted to engage with a contact, 8^a, depending from the plate 5. The other arm has a link-connection, 10, leading from its 55 extremity to a cross-head, 12, on a vertical slide-bar, 13, which passes through both the plate 5 and the spider 3 and moves freely in each. Upon the lower extremity of each arm is a contact-shoe, 14, adapted to make connection with 60 and move upon the cable. Wires 15 lead from each of the contacts 8^a to the binding-posts 16, whereby the current is carried to the motor.

In order to balance the weight of the bar 13, a light spring, 17, may, if desired, be interposed between the plate 5 and a disk or head, 18, rigid upon said bar.

It will be seen that by pushing downward upon the vertical slide-bar 13 the arms 7 may both be instantly raised out of contact with 75 the cable, either to arrest the motor or to cross some intersecting cable. At the same time, when the car is in motion, the rocking and swaying of the car-body, as well as the rise and fall thereof, by reason of the entrance or 80 departure of passengers, will be compensated by the rise and fall of the plate 5, which carries the arms 6, to which the contact-arms 7 are pivoted, as well as the contacts 8^a, the arrangement shown giving a perfectly-uniform 85 contact at all times and under all circumstances.

I prefer to form the pivotal bearings of the contact-arms, as shown in Fig. 4, by setting a glass or vitreous bearing, 19, in an opening in 90 the arm, said bearing having a flange, 20, on one end. A boss or lug, 21, is formed on each side or face of said arm, surrounding the bearing, and on one of said lugs I mount a wooden annulus, 22, secured in place by screws 23, or 95 equivalent means. This annulus overlaps the flanged end of the bearing and holds it in place.

The invention described is adapted for use in connection with the electric subway covered by an application, Serial No. 260,572, filed by me of even date herewith.

5. What I claim is—

1. The combination, with a car or other conveyance having an electric motor, of contact-arms taking the current from a subway to said motor, a vertically movable support upon which said arms are pivotally mounted and carrying the electrical contacts with which they engage, and guides giving vertical movement to said support, substantially as described.
15. 2. The combination, with vertical guides having a spider or plate rigidly mounted thereon, of a support movable on said guides and having brackets or arms with electrical contacts arranged upon said brackets, and arms pivoted to the latter and having contact-arms and springs interposed between the support and spider, substantially as described.
25. 3. The combination, with vertical guides having a plate or spider mounted thereon, of a support movable on said guides and provided with brackets and contacts, arms pivotally mounted on said brackets and having contact-arms engaging with the contacts on the movable support, a vertical slide-bar having a link-connection with an arm on each contact-arm, and springs interposed between the support and the spider, substantially as described.

4. The combination, with vertical guide-bars having a spider connecting their upper ends, of a support movable upon said bars, springs interposed between said support and the spider, contact-arms pivotally mounted on brackets depending from said support, a vertical slide-bar carried through the spider and the movable support and having link-connections to arms projecting from the contact-arms at or near the pivotal points of the latter, and a spring giving support to the vertical slide-bars, substantially as described. 45

5. The combination of the swinging contact-arm having an opening and opposite bosses surrounding the ends of the opening, the vitreous bearing inserted in the opening, and an annulus attached in a fixed position to one of the bosses and overlapping one end of the vitreous bearing, substantially as described. 50

6. The combination, with a contact-arm having one or more openings and provided with surrounding lugs or bosses, of a vitreous bearing having a flanged end, and a non-conducting annulus overlapping said end and secured to one of said lugs, substantially as described. 55

In testimony whereof I have affixed my signature in presence of two witnesses.

JOSHUA KAMES.
